UNITED STATES PATENT OFFICE

2,366,062

MACHINE FOR OPENING OR LAPING WIRE DRAWING DIES AND THE LIKE

Donald F. Sengenberger, Waukegan, Ill., assignor to The American Steel and Wire Company of New Jersey, a corporation of New Jersey

Application September 21, 1943, Serial No. 503,250

12 Claims. (Cl. 51—31)

This invention relates to a die opening or lapping machine, and more particularly to an improved multiple spindle machine, especially adaptable for opening wire drawing dies and the like.

Wire drawing dies are generally furnished by the manufacturer thereof to the wire or steel industry, either in the form of blanks which are only partially pierced or blanks completely pierced to a predetermined hole size. Partially pierced die blanks are provided merely with a conical-shaped entrance opening and without a bearing portion therein, or opening completely through the blanks. It will be understood that it is the bearing portion that actually draws the wire to size as it is pulled through the die. Die blanks are furnished in such condition in order that the user may open them so as to provide therein a bearing portion or opening of the desired diameter, being in most cases fine wire sizes.

Such die blanks are usually made of tungsten carbide or a similar hard material, and are generally opened, so as to form the desired entrance angle or contour therein by the process of lapping or ripping by means of a revolvable tool or drill consisting of a tapered needle or pin having an extremely sharp point for forming the opening through the die blanks. An abrasive material or lapping powder, such as boron carbide, silicon carbide, diamond powder or a similar abrasive mixed with water, olive oil or any other suitable fluid is generally used as the abrasive in the lapping or ripping operation.

Also, oftentimes it is the practice in the wire industry to enlarge the bearing portion or opening in wire drawing dies so as to provide a die of the next larger size. That is, when a die becomes worn out and is drawing oversize wire and consequently, is of no further use for drawing the size wire for which it was originally intended, the die opening or bearing portion is ripped to the next size or, perhaps the second or third size thereabove depending upon the demand for such size dies and how much oversize the particular die happens to be. It will be understood that before a used or worn out die can be placed back in service again, it must necessarily have the worn, irregular and roughened surfaces removed therefrom before being sized and polished. A worn out die generally has an annular mark on the surface of the entrance angle, i. e., at the point where the wire being drawn enters the die and first makes contact therewith, and the bearing or straight portion

frequently becomes grooved or scratched. Therefore, in order to place this die in condition for use again, all of the foregoing irregularities must be removed therefrom and a smooth contour once again established.

Accordingly, it is the general object of the present invention to provide an improved machine which can be conveniently used either for lapping, ripping, opening or polishing the inner contours of wire drawing dies and the like.

It is another object of the invention to provide an improved machine for conditioning wire drawing dies wherein a multiplicity of die or die blanks are worked upon by a multiplicity of tools at one time, and a machine wherein the cutting or drilling tools are both rotated and simultaneously reciprocated relative to their respective dies so as to form properly the contours therein.

It is a further object of this invention to provide an improved machine for opening wire drawing dies having a multiple of rotatable spindles which is simple and inexpensive in its construction, and, at the same time, efficient and effective in its use.

It is still another object of the present invention to provide an improved multiple rotatable spindle machine for opening wire drawing dies wherein the opening tools are so disposed in the spindles so that any one or all of the tools may be easily and quickly removed from their position in the machine while the same is in operation.

It is still a further object of this invention to provide an improved means for supporting the cutting or drilling tool in a die opening machine wherein the cutting or drilling tool is floatingly disposed and frictionally driven so that the weight of the tool itself is the sole means for feeding the same into the die.

Various other objects and advantages of this invention will be more apparent in the course of the following specification and will be particularly pointed out in the appended claims.

In the accompanying drawings there is shown, for the purpose of illustration, an embodiment which my invention may assume in practice.

In these drawings:

Figure 1 is a plan view of the improved machine of my invention for conditioning wire drawing dies;

Figure 2 is a sectional view taken on line II—II of Figure 1;

Figure 3 is a sectional view taken on line III—III of Figure 1;

Figure 4 is a sectional view taken on line IV—IV of Figure 1; and

Figure 5 is a sectional view taken on line V—V of Figure 1 showing how the cutting or drilling tool is disposed in each of the spindles.

Referring more particularly to the drawings, the improved machine of my invention comprises a stationary frame or base 2, upon which there is mounted preferably a horizontally disposed plate-like rotatable platform or turn-table 3. The platform 3 is supported centrally thereof, preferably by means of a bearing 4 consisting preferably of upper and lower plates 5 and 6, respectively, with the upper plate 5 attached to the bottom of the platform 3 and with the lower plate 6 attached to the base 2 and having a ball race 7 with ball bearings 8 arranged therein.

There is mounted on the rotatable platform 3 at a spaced distance thereabove preferably secured thereto by means of spacer bolts 9, preferably a horizontally disposed circular plate-like member 10. On the upper side of the plate-like member 10 adjacent the edge thereof, there is arranged therearound a plurality of spaced apart circular depressions or recesses 12, nineteen in the present instance, with a hole 13 arranged through the member 10 opposite each of the recesses centrally thereof, and communicating therewith. There is adapted to be disposed in each of the recesses 12, a workpiece or circular wire drawing die D to be worked upon so as to provide a circular arrangement of the workpieces.

Above the plate-like member 10, there is arranged a pair of horizontally disposed vibrating plate-like members 14 and 15, which are preferably spaced apart and connected to each other by means of a plurality of spacer bolts 16. There is carried by the plate 10, preferably a plurality of upwardly extending guide bolts 17 which extend upwardly through both of the plates 14 and 15, and there is arranged on the upper end of each of the bolts 17, preferably a coil spring 18 and a nut 19. The springs 18 are positioned directly above the upper plate 14 with the springs adapted to cooperate therewith for a purpose hereinafter to be described.

Between the pair of plates 14 and 15 there is positioned in a circular arrangement, a plurality of vertically disposed spindles 20 with the ends thereof suitably journaled in the plates 14 and 15 by means of the roller bearings 21. Each of the spindles 20 has an axial hole 22 arranged therethrough in which there is disposed a cylindrical cutting or drilling tool 23. The tool 23 is preferably in the form of a longitudinally extending pin having an extremely sharp tapered drilling point 24 arranged on one end thereof. Each of the tools or pins 23 is preferably of such length that it protrudes from the upper end of the spindle 20 when positioned therein, as more clearly shown in Figure 5 of the drawings for a purpose to be later described. It will be understood that each of the spindles 20 is positioned directly above one of the recesses 12 and the workpiece D adapted to be disposed therein of the plate 10 so that the tool 23 carried thereby is disposed directly above the center of the workpiece or die. The member 23, instead of a tool, may be a cylindrical tool holder having a chuck arranged on the lower end thereof for holding a relatively small tool in the form of a pin, if desired.

Centrally of the plates 10, 14 and 15, and concentric therewith, there is positioned a vertically

disposed drive shaft 25 with the lower end thereof positioned in a suitable bearing 26 carried preferably by an inverted U-shaped bracket member 27 suitably mounted on the rotatable platform 3 and secured thereto centrally thereof preferably by means of cap screws 28. Between the pair of plates 14 and 15, there is securely arranged on the shaft 25 preferably a plurality of pulleys 29, three in the present instance, and there is securely arranged on each of the spindles 20, a pulley 30. There is disposed around one of each of the pulleys 29 of the shaft 25 and a plurality of the pulleys 30 on the spindles 20, in a zigzag manner, a plurality of belts 31, three in the present instance, so that a plurality of spindles are driven by one of the belts. In other words, each of the belts 31 drives a group of spindles, and all of the groups of spindles are driven simultaneously upon rotation of the shaft 25 through the action of the pulleys 29 securely attached thereto. It will be understood that the pulleys 30 on the spindles 20 are arranged thereon at different levels, three in the present instance, in order to facilitate the horizontal arrangement of the belts 31.

Preferably at a point below the lowermost plate-like circular member 10, there is securely arranged on the shaft 25, another pulley 32. There is mounted on the platform 3, preferably an electric motor 33 having a shaft 34 upon which there is mounted a pulley 35. There is arranged around the pulley 35 and the pulley 32 on the shaft 25, a belt 36 through which the motor 33 is adapted to drive the shaft 25 together with all of the spindles 20.

As more clearly shown in Figures 3 and 4 of the drawings, there is arranged centrally of the platform 3 and diametrically thereof, a horizontally disposed cam shaft 37, which extends through the bracket member 27 and is preferably journaled in a pair of spaced apart bearings 38 carried by a pair of spaced bracket members 39 arranged to either side of the bracket 27 and mounted on the platform 3 in any suitable manner. There is securely arranged on the cam shaft 37, a pulley 40, and there is disposed around both the pulley 40 and another pulley 41 arranged on the shaft 34 of the motor 33, another belt 42 for driving the cam shaft 37.

There is carried by the lowermost plate 15 of the pair of plates, preferably a pair of spaced apart downwardly extending stud-like members 43, which are preferably diametrically arranged from each other directly above the cam shaft 37. The stud-like members 43 extend through the lowermost plate 10, and the bottom ends thereof rest against the peripheries of bearings 44 arranged on each end of the cam shaft 37. In other words, the stud-like members 43 act as cam followers of the cam shaft 37.

As shown in Figure 2 of the drawings, there is mounted on the rotatable platform 3, at a point directly below each of the openings 13 of the circular member 10, preferably a bracket member 45 having an inclined shelf portion 47 on which there is disposed a mirror 46. Each of the mirrors 46 is so positioned thereon that it can be seen from the outer side of the machine, and so that the under side of the die D adapted to be positioned in the recess 12 directly opposite the hole 13 in the plate 10, can be seen or viewed therethrough for a purpose hereinafter to be described.

There is also mounted on the upper side of the platform 3, preferably a pair of spaced apart

knob-like handle members 48 whereby the platform 3 and the entire machine may be rotated through 360°. There is arranged on the lower side of the platform 3, preferably a plurality of rollers 49. It will be understood that the bearing 4, together with the rollers 49, rotatably support the machine.

The improved machine of my invention operates in the following manner. The workpieces or dies D are positioned in the recesses 12 of the work plates 10 whereby a circular arrangement of the workpieces or dies is provided. A tool or pin 23 is then inserted in the axial hole 22 of each of the spindles 20 so that the sharpened point 24 thereof contacts the respective workpieces or dies D positioned therebelow, as more clearly shown in Figure 5 of the drawings. The machine is now ready to be set in operation, and the motor 33 is energized so as to set the shaft 34, together with the belts 36 and 42 disposed around the pulleys 35 and 41, in motion. It will be seen that upon rotation of the shaft 34 on the motor 33, that the shaft 25 of the machine will be rotated due to the action of the belt 36 and the pulley 32. Upon rotation of the shaft 25, it will be seen that all of the spindles 20 are driven due to the action of the belts 31 and the pulleys 29 and 30 around which they are disposed. Upon rotation of the spindles 20, it will be seen that each of the tools or pins 23 carried thereby will also be rotated due to frictional contact between the tools and their respective spindles. Each of the cylindrical tools or pins 23 is preferably coated with a layer of heavy grease before they are inserted in the axial holes 22 of the spindles 20 in order to insure a better frictional contact and a more positive drive between the walls of the holes through the spindles. If a separate tool holder is used, it will be understood that both the tool holder together with the tool or pin carried thereby will be floatingly disposed in the axial holes of the spindles.

Upon energization of the motor 33, it will be seen that the shaft 34 thereof, also drives the cam shaft 37 due to the action of the pulleys 40 and 41 and the belt 42 disposed therearound. As the cam shaft 37 rotates, it will be seen that the pair of plates 14 and 15 are reciprocated vertically, due to the cooperation of the downwardly extending stud-like members 43 with the roller bearings 44 arranged on either end of the cam shaft 37. In other words, the pair of plates 14 and 15 are lifted vertically upon each revolution of the cam shaft 37 against the action of the coil springs 18 carried by the guide bolts 17 above the uppermost plate 14. It will be understood that it is the purpose of the coil springs 18 to maintain the ends of the stud-like members 43 against the bearings 44 so as to provide a relatively quick return for the pair of plates after they have been lifted. In other words, the springs 18 are provided so as to prevent any lag in the downward movement of the plates 14 and 15 so that the plates are forced positively downwardly. It will be seen that each of the tools or pins 23 are all rotated at the same time and simultaneously reciprocated relative to their respective workpieces or dies D. In the present machine, the plates 14 and 15 are lifted and lowered approximately one sixteenth of an inch from their intermediate positions and reciprocate approximately 875 times a minute, the total plate vertical movement being about one eighth of an inch. In other words, the ends of the cam shaft 37 upon which the roller bearings 44 are

positioned are off-center approximately one sixteenth of an inch on the diameter.

It will be understood that each of the tools or pins 23 is floatingly disposed in the axial hole 22 of each of the spindles 20 and this is one of the most important aspects of the present invention, inasmuch as in any die lapping operations, the point of the tools or pins 23 necessarily have to be reground or sharpened periodically in order to maintain the proper taper and point thereon. It is preferable that each of the tools or pins 23 has a relatively close fit with the holes 22 in the spindles 20, but not too tight a fit. In other words, the clearance between the outer side of the tool 23 and the wall of the hole 22 should be sufficient to permit telescopic movement of the tool therein so that the tool can be easily removed therefrom by grasping the upper end thereof while the spindles are turning and the machine is operating. The bore 22 in the spindles 20 is preferably from .002 to .005 of an inch greater than the outer diameter of the tool or pins 23. It will be understood that sufficient friction is created between the tool and the walls of the holes in the spindles to cause the tool to be lifted during the rotation thereof when the plates 14 and 15, which carry these spindles, are reciprocated thereby permitting sufficient cutting fluid which is manually placed on the workpieces or dies to reach the point of the tool. It will be understood that no feed is provided for the tool other than the weight of the tool itself. In other words, it is important that the tool be of sufficient weight to make it self-feeding.

To understand the foregoing, it is only necessary to consider that the frictional force given each tool by its spindle depends on the moving direction and speed of the spindle. Therefore, the rotative force given the tool is sufficient for the tool to do its work since the spindle rotates continuously in the same direction at high speed, and the lifting force is sufficient to lift the tool while the spindle moves upwardly but is insufficient to prevent the tool from falling when the spindle moves downwardly. Also, since the force depends on the moving speed of the spindle, by rotating the spindle at a peripheral rate exceeding its lineal speed while moving up and down, adequate rotary force can be given the tool without preventing its being raised and dropped as described.

During the operation of the machine, the mirrors 46 positioned on the under side of the workpieces or dies D are periodically observed so as to view the bottom side of the respective dies positioned thereabove. This is done in order to ascertain when the opening is completely formed through the workpieces or dies D. When the tool has passed through any particular workpiece or die, a spot of cutting fluid appears on the under side thereof and this can be readily seen in the mirrors 46. By providing such an arrangement, it will be seen that it is not necessary to remove the workpieces or dies from the machine for ascertaining whether or not the opening is completely formed therethrough. It is important that the drilling operation be stopped and the workpiece or die removed from the machine as soon as a hole or opening is formed through the workpieces or dies, in order to prevent the forming of an oversize opening in the dies.

The knob-like handles 48 on the platform 3 are provided for rotating the entire machine so as to make the operation of the same more con-

venient for the operator. In other words, the machine revolves on the turn-table center provided by bearing 4 thereby making it possible for the operator to observe the under side of the dies or workpieces by the aid of the mirrors 46 and to remove the dies or tools without being inconvenienced by reaching around any part of the machine. It will be understood that any one of the workpieces or dies D, or any one of the tools or pins 23, may be removed from or replaced in the machine while the same is in operation. The top plate 14 of the pair of plates preferably has openings in the top thereof, as shown in Figure 1 of the drawings, so as to facilitate the placing of the belts 31 around the pulleys 30 of the spindles 20 and the pulleys 29 of the shaft 25.

As a result of my invention, it will be seen that there is provided an improved machine for opening, ripping, or polishing wire drawing dies which is extremely simple both in its construction and use. By providing such a machine, it will be seen that a multiplicity of dies can be worked on at one time by a single operator. In the machine of my invention, it will be seen that any one of the cutting or drilling tools may be quickly and conveniently removed from the machine while the same is in operation, and replaced with a new or sharpened tool. It will be seen also that the tools or pins are not only rotated by the machine, but are likewise reciprocated during the rotation thereof so as to permit the cutting fluid to repeatedly reach the point of the tools or pins, and thus efficiently carry out their lapping operations.

While I have shown and described one specific embodiment of my invention, it will be understood that this embodiment is merely for the purpose of illustration and description and that various other forms may be devised within the scope of my invention, as defined in the appended claims.

I claim:

1. A machine of the class described, including a horizontally disposed member having a plurality of openings arranged therein for holding a plurality of workpieces, a second horizontally disposed member positioned above said first mentioned member, a plurality of revolvable tool holding means rotatably mounted on said last mentioned member with one adapted to be positioned opposite the position each of the workpieces is adapted to assume, each of said tool holding means adapted to support a tool for forming a hole in its respective workpiece, means for rotating each of said tool holding means simultaneously, and means for reciprocating vertically said last mentioned member simultaneously with the rotation of the tools carried thereby whereby the tools will be reciprocated relative to their respective workpieces.

2. A machine of the class described, as defined in claim 1, wherein each of the tools is floatingly disposed in its respective tool holding means so as to be frictionally driven thereby and whereby any one of the tools can be removed from its position therein while the machine is in operation.

3. A machine of the class described, as defined in claim 1, including a mirror arranged below the first mentioned member directly below the openings therein for ascertaining when the hole is completely formed through the workpiece by its respective tool.

4. A machine of the class described, includ-

ing a horizontally disposed circular plate-like member having a plurality of openings arranged concentrically therein for supporting a plurality of workpieces in a circular arrangement, a second horizontally disposed circular plate-like member positioned above said first mentioned plate-like member concentric therewith, a plurality of revolvable tool holding spindles mounted on said second mentioned plate-like member in an annular arrangement concentric therewith with one adapted to be positioned opposite each of the openings and the workpiece adapted to be positioned therein of said first mentioned plate-like member, each of said tool holding means adapted to support a tool for forming a hole in a workpiece positioned therebelow, a vertically disposed rotatable shaft extending through both of said plate-like members and arranged concentric therewith, means for driving said shaft, driving means interconnecting said shaft with each of said spindles whereby each of the spindles together with the tools carried thereby are rotated simultaneously upon rotation of said shaft, and means arranged below said second mentioned plate-like member for reciprocating the same vertically whereby the tools carried by said spindles will be reciprocated relative to their respective workpieces simultaneously with the rotation of the tools.

5. A machine of the class described, as defined in claim 4, wherein each of the tools is floatingly disposed in the spindles so as to be frictionally driven thereby and whereby any one of the tools may be removed from its position in the spindle while the machine is in operation.

6. A machine of the class described, as defined in claim 4, wherein the means arranged below the second mentioned plate-like member for reciprocating the same vertically consists of a horizontally arranged cam shaft including means for driving the same.

7. A machine of the class described, as defined in claim 4, wherein the means interconnecting the shaft with each of the spindles for rotating the same consists of a plurality of pulleys arranged on said shaft and a pulley arranged on each of said spindles, and a plurality of belts with each of the belts disposed around one of the pulleys on said shaft and several of the pulleys of a group of said spindles whereby the spindles of each group and all of the groups of spindles are driven simultaneously by said shaft and said belts.

8. A machine of the class described, including a horizontally disposed platform rotatably mounted, a horizontally disposed plate-like member secured thereto and positioned thereabove having a plurality of openings circularly arranged therein for receiving and supporting a plurality of workpieces, a pair of spaced apart horizontally disposed plate-like members arranged above said last mentioned plate-like member and secured thereto, a plurality of vertically disposed rotatable hollow spindles circularly arranged between said pair of plate-like members, a vertically disposed removable tool consisting of a pointed pin-like member arranged in the hollow portion of each of said spindles, each of said spindles together with the tool carried thereby being positioned directly opposite an opening in said first mentioned plate-like member, so as to be disposed directly opposite the workpieces adapted to be positioned therein, a vertically disposed shaft extending through each of said plate-like members and arranged concentric therewith,

at least one pulley arranged on said shaft between said pair of plate-like members, a pulley arranged on each of said spindles, a belt arranged around the pulley on said shaft and the pulleys on said spindles, means for rotating said shaft whereby all of the spindles together with the tools carried thereby are rotated simultaneously, and means arranged below the lowermost plate-like member of said pair of plate-like members for reciprocating the same vertically whereby the spindles together with the tools carried thereby will be reciprocated relative to their respective workpieces simultaneously with the rotation of the spindles and tools.

9. In a machine for opening or enlarging wire drawing dies and the like, a horizontally disposed member having a plurality of openings arranged therein in which the dies are adapted to be positioned, a pair of spaced apart horizontally disposed members arranged above said first mentioned member and securely attached thereto and to each other, a plurality of vertically disposed axially hollow spindles rotatably arranged between said pair of members with one arranged directly opposite each of the openings in said first mentioned member, a removable tool telescopically arranged in the hollow portion of each of said spindles which is adapted to open or enlarge the hole in the respective dies, each of said tools being floatingly disposed in their respective spindles so as to be driven frictionally thereby and whereby any one of them can be removed from or replaced in the spindles while the same are rotating and the machine is in operation, means for driving each of said spindles simultaneously, a camming mechanism arranged below the lowermost member of said

5 pair of members and in engagement therewith whereby the pair of members together with the spindles and tools carried thereby are reciprocated vertically so that the tools are reciprocated relative to their respective workpieces simultaneously with the rotation of the spindles and the tools carried thereby.

10. In a machine for opening or enlarging wire drawing dies and the like, the combination as defined in claim 9, including a mirror arranged below the openings in the first mentioned member which is adapted to be disposed directly below the die therein whereby the bottom of the die can be viewed therethrough so as to ascertain when the tool has completely opened the hole in the respective dies.

15. In a machine for opening or enlarging wire drawing dies and the like, the combination as defined in claim 9, including resilient means arranged above the uppermost member of the pair of circular members tending to force the same downwardly so as to counteract the upward lift of the same by the camming mechanism for reciprocating the pair of members whereby the pair of members will be moved rapidly downwardly and maintained in contact with the cam of the camming mechanism.

20 25 30 35 11. In a machine for opening or enlarging wire drawing dies and the like, the combination as defined in claim 9, including resilient means arranged above the uppermost member of the pair of circular members tending to force the same downwardly so as to counteract the upward lift of the same by the camming mechanism for reciprocating the pair of members whereby the pair of members will be moved rapidly downwardly and maintained in contact with the cam of the camming mechanism.

12. In a machine for opening or enlarging the openings of wire drawing dies and the like, the combination as defined in claim 9, wherein the camming mechanism comprises a horizontally disposed cam shaft having a bearing portion arranged on each end thereof which cooperates with means for lifting vertically the pair of members, and means for rotating said cam shaft.

DONALD F. SENGENBERGER.
